UNITED STATES PATENT OFFICE.

VICTOR EDWARD LANE, OF BERWICK, PENNSYLVANIA.

PNEUMATIC HAMMER.

1,007,295.

Specification of Letters Patent. Patented Oct. 31, 1911.

Application filed June 21, 1909. Serial No. 503,320.

To all whom it may concern:

Be it known that I, VICTOR EDWARD LANE, a citizen of the United States, and a resident of Berwick, in the county of Columbia and State of Pennsylvania, have invented a new and Improved Pneumatic Hammer, of which the following is a full, clear, and exact description.

My invention relates to pneumatic hammers, and has for its object to provide a detachable nose piece carrying the rivet set, or equivalent tool, and so arranged that the nose piece, when removed from the barrel, carries with it the rivet set, while the rivet set is in turn detachable from the nose piece independently of whether the latter be mounted upon the barrel or not.

A further object of the invention is to provide a simple, cheap and efficient means 20 for securing the nose piece to the barrel.

Reference is to be had to the accompanying drawings forming a part of this specification, in which similar characters of reference indicate corresponding parts in all 25 the figures.

Figure 1 is a substantially central vertical section through the entire hammer, and showing the relation of the plunger, the movable sleeve, the barrel, and rivet set and 30 the handle; Fig. 2 is an enlarged cross section on the line 2—2 of Fig. 1, looking in the direction of the arrow, and showing how the rivet set is detachably mounted in relation to the nose piece; Fig. 3 is a section 35 upon the line 3—3 of Fig. 1, looking in the direction of the arrow, and showing how the nose piece is detachably connected with the barrel; Fig. 4 is an enlarged cross section upon the line 4—4 of Fig. 1, looking 40 in the direction of the arrow and showing how the barrel and the movable sleeve encircled by it are put together; Fig. 5 is an enlarged section substantially upon the line 45 5—5 of Fig. 1, looking in the direction of the arrow, and showing the spring and parts associated therewith for retracting the air valve to its normal position; and Fig. 6 is a detail showing a portion of the spring band appearing in Fig. 3, and showing a 50 hole through the abutting ends of said band to facilitate the application of a tool for the purpose of loosening and removing the band and the pins carried by it. Fig. 7 is a detail 55 showing the valve spring and parts associated therewith.

The handle of the hammer is shown at 7,

the outer sleeve at 8 and the inner sleeve at 9, these two sleeves being held rigidly together as hereinafter described, and together constituting practically a barrel.

At 10 is a sleeve slidably mounted within the sleeve 9 and somewhat shorter than the latter.

At 11 is a nose piece, and supported by the same is a rivet set 12 provided with a 65 stem 47 which extends slidably into the nose piece.

The handle 7 is provided with a groove 13, and pivotally mounted within this groove is a lever 14. Slidably mounted 70 within the handle 7 is a valve stem 15 which is engaged by the lever 14. A valve 16 is connected with the valve stem 15 and thus actuated by movements of the lever 14.

The handle 7 is provided with an air passage 17 which is connected up with a suitable source of air supply, for the purpose of actuating the hammer. Communicating with the air passage 17 is a valve chamber 18 in which the valve 16 is slidably 80

mounted. A spiral spring 19 engages the valve 16 and is held in position by a cap 20. This cap is provided with an annular flange 21 having pins 21^a projecting inwardly from the same. A boss 22 integral 85

with the handle 7 is of proper size for this cap to fit upon, and is provided with longitudinal grooves 23, which reach and merge into a single annular groove 23^a. The boss 22 is further provided with two notches 22^a 90

merging into the annular groove 23^a. In placing the cap 20 upon the boss 22, the pins 21^a carried by the cap are fitted into the longitudinal grooves 23, and the cap is then 95

pushed to the left according to Fig. 1, so that the pins 21^a enter the groove 23^a. The cap is now given a quarter of a turn, so 100

that the pins pass into the notches 22^a. The spiral spring 19 being under compression causes the pins 21^a to snap into the notches 105

22^a as soon as the cap is turned as just described for this purpose. The cap 20 is thus effectively locked in position, but is nevertheless so held that the operator may 110 at will readily disengage it. This he does by giving it another quarter of a turn, meanwhile pressing upon the cap so as to slightly compress the spring 19.

The inner sleeve 9 of the barrel is provided with air passages 25 and 25^a, shown in 115 Figs. 1 and 4. The air passage 25 extends from a hole 26 in this sleeve to a hole 32 in

the same member. The passages 25^a extend from a hole 36 to another hole 36^a in the sleeve 9. The passages 25^a meet and merge into an annular groove 42 in the handle 7. 5 A series of holes 41 connect this annular groove 42 with the air passage 17, thus allowing free travel of air from the passage 17 in the barrel to the passages 25^a. The inner sleeve 9 of the barrel is also provided 10 with holes 36, 36^a, which communicate with the passages 25^a. The inner sleeve 9 and the sleeve 8, which encircles it, are provided with holes 37, 38, 39, 40, extending into rows around the barrel and entirely through both 15 sleeves 8 and 9. The barrel, as a whole, comprising the inner sleeve 9 and the outer sleeve 8, is also provided with holes 31^b and 32^a, which extend entirely through the barrel and are located between the passages 25 20 and 25^a. The hole 32^a extends through the handle 7. The slidable sleeve 10 is provided with oil grooves 29, which are used to facilitate the lubrication of this sleeve. The slidable sleeve 10 is also provided with 25 annular grooves 28, 28^a, 30 and 31 and with holes 30^a, 31^a, 27^a and 35. An anvil cap 33 is connected rigidly with the slidable sleeve 10. The plunger of the hammer is shown at 34 and slidably mounted within the sleeve 10. 30 The uses of the various air passages, grooves and holes just mentioned are hereinafter more completely described.

The sleeve 8 is provided with a sloping edge 41 and in registry with the latter the 35 sleeve 9 has a sloping edge 42, this sloping edge being the boundary or end of the thin portion 42 of the sleeve last mentioned. The nose piece 11 is provided with a shoulder 43, this shoulder having a sloping wall, 40 as indicated in Fig. 1, for the purpose of holding the sleeves 8, 9 more securely in position and thus preventing the incessant jarring of the hammer due to the reciprocating action of the plunger 34 from shaking the sleeves 8, 9 loose relatively to each 45 other and to the nose piece 11. A spring band 44 having its ends 45 turned inwardly is sunken into the sleeve 8 and is provided with a hole 44^a, as indicated in Fig. 6, this 50 hole mutilating the inturned ends 45, as will be understood from said figure. The purpose of this arrangement is to facilitate the entrance of a tool into the hole 44^a for the purpose of facilitating the removal of the 55 spring band 44, as hereinafter described. The spring band 44 carries pins 46 disposed internally of the band and extending toward the central longitudinal axis of the hammer. The pins 46 and spring band 44 60 together normally hold the nose piece 11 upon the barrel which, as above described, is made up of the outer sleeve 8 and the inner sleeve 9.

The rivet set 12 is provided with the 65 stem 47 extending into the nose piece

11, this stem being encircled by a groove 48. Another spring band 49 is sunken into the nose piece 11 and encircles the same, as indicated in Figs. 1 and 2. A number of pins 50, provided respectively with heads 70 51, extend radially into the nose piece 11 and are provided at their inner ends with beveled portions 52 which extend into the groove 48 and normally prevent the removal of the stem 47, thus retaining the rivet set 75 12 in engagement with the nose piece 11. The spring band 49 is provided with an inwardly turned end 53 which extends radially into the nose piece 11, as indicated in Fig. 2. 80

In order to remove the rivet set 12 it is grasped by the hand and given a sharp jerk outwardly, so that a portion of the stem 47 strikes against the beveled ends 52 of the pins 50 driving these pins radially outward contrary to the tension of the spring band 49, the stem 47 being thus readily detached from the nose piece. If it happens, in a particular case, that this fails to dislodge the rivet set, the operator may, by displacing or removing the spring band 49, take out the pins 50, or loosen the same, and thus readily remove the rivet set from its fastenings. 85

The nose piece 11, containing the rivet 95 set or not, as desired, may be removed bodily from engagement with the outer and inner sleeves 8, 9. This is best accomplished by placing a tool, such as a nail or a small bolt, into the hole 44^a (Fig. 6) and prying the 100 inwardly turned ends 45 slightly outward, thereby disengaging the spring band 44, the removal of which renders the pins 46 loose and the latter can then be readily taken out. This being done, the nose piece 11 drops off, or 105 is easily moved. In making up the hammer barrel I place the inner sleeve 9 within and concentric to the outer sleeve 8 and shrink or press them together, so that they will adhere firmly. Then, when the nose piece 110 11 is placed in position, as above indicated, it locks them even more securely than before. The barrel thus being formed, it is connected with the handle 7 by being first 115 inserted slightly into the same, as indicated in Fig. 1, and then brazed, soldered or welded, as desired.

The operation of my device is as follows: The passage 17, being in communication with a suitable supply of air under pressure, 120 and the parts being arranged as indicated in Fig. 1, the operator presses upon the lever 14, thereby displacing the barrel 16 and admitting the air unto the hammer. The air finds its way from the passage 17 to the 125 holes 41' and into the annular groove 42, from whence it goes into the air passages 25^a, and the holes 36, at the ends of the passages 25^a being now closed owing to the 130 position of the movable sleeve 10, the air

passes through the holes 36^a into the barrel and follows the annular groove 33^a in the movable sleeve, passing through the holes 30^a and 31^a into the interior of the movable sleeve 10 and back of the plunger 34. The pressure of this air starts the plunger upon its down stroke. The air in front of the plunger, having a free exhaust through the holes 37, 38, 39 and 40, offers no obstruction to the stroke of the plunger. When the plunger has nearly reached the end of its down stroke, the air escapes through the holes 27 in the movable sleeve and into and around the annular groove 28. The air then passes back through the groove 25 and through the holes 32 into the interior of the barrel, back of the movable sleeve 10. The cross section area of this opening, back of the sleeve 10, being larger than the cross section area inside of the movable sleeve 10, the pressure back of the sleeve 10 overcomes the pressure inside of this sleeve and thus shifts the movable sleeve forward a trifle or enough to close the holes 31^a, 27, 37, 38, 39 and 40, and to bring the holes 36 into registry with the holes 35 and with the annular groove 28^a in the movable sleeve 10. The hole 31^b is also brought into registry with the annular groove 31 and the holes 30 in the movable sleeve. The forward or down stroke of the movable sleeve opens the hole 32^a, which allows the air after performing its mission of moving the sleeve 10 as described, to escape, the air passing out of the hole 32^a. The down stroke of the plunger having thus been accomplished and the movable sleeve following directly after and the holes 31^a being now closed, the holes 36 and 35 being in registry, the air passes through these holes into the interior of the movable sleeve and in front of the plunger 34. This starts the plunger on its back stroke. The air ahead of the plunger upon this back stroke is exhausted through the holes 30 and the annular groove 31 in the movable sleeve and through the hole 31^b in the barrel, these holes being now in registry. The plunger 34 now reaches and closes these openings, whereupon the balance of the air between the plunger and the cap 33 of the movable sleeve 10 forms momentarily a cushion, thus preventing a violent blow between the plunger 34 and the cap 33. The back stroke of the plunger,

however, shifts the movable sleeve 10 back 55 into its first position, as indicated in Fig. 1. The reciprocating movement of the plunger 34 and the movable sleeve 10 continues as above described so long as the air pressure is allowed to enter the hammer. While the 60 up stroke of the plunger is cushioned, the down stroke ends in a dead or solid blow.

The device is so arranged that the back stroke of the plunger 34 is actuated slightly by the action of the air. The inner sleeve 65 9 and the outer sleeve 8, put together as above described, constitute the barrel of the hammer and this barrel, as is apparent from the foregoing description, is provided with various air passages 25 which communicate 70 with various air holes.

While barrels for pneumatic hammers have heretofore been constructed and provided with passages somewhat analogous to the air passages 25, the manufacture of such 75 barrels has been difficult, owing to the labor and expense of boring the air passages in question.

Having thus described my invention, I claim as new and desire to secure by Letters 80 Patent:

1. In a pneumatic hammer, the combination of a barrel having its end inclined downwardly and outwardly, a nose piece provided with a shoulder inclined downwardly and outwardly with which the end of the barrel engages, the inclined end of the barrel and the inclined shoulder of the nose piece serving to aid in holding the barrel and nose piece together, and fastening 85 members for holding said nose piece detachably in position upon said barrel.

2. In a pneumatic hammer, the combination of a barrel, a nose piece extending into the barrel, a band surrounding the barrel 95 and having inturned ends sunken into the barrel, an opening being formed in the band at the inturned ends, and pins carried by the band and passing through the barrel into engagement with the nose piece. 100

In testimony whereof I have signed my name to this specification in the presence of two subscribing witnesses.

VICTOR EDWARD LANE.
